Fig. 1

Fig. 3

FIG. 1 is an elevational view of a bottle showing my new design;

FIG. 2 is a perspective view taken from the opposite side thereof; and

FIG. 3 is a top plan view thereof.

The characteristic feature of my design resides in the portion shown in full lines and consists in the combination on the generally cylindrical bottle of the nipped-in grooved band about the lower central portion as shown.

I claim:

The ornamental design for a bottle or similar article, as shown and described.
